UNITED STATES PATENT OFFICE.

LEANDER P. BONNELL, OF NORTH EAST, PENNSYLVANIA

DEVICE FOR PREVENTING THE CREEPING OF RAILS.

No. 905,835.

Specification of Letters Patent.

Patented Dec. 8, 1908.

Application filed March 2, 1908. Serial No. 418,722.

To all whom it may concern:

Be it known that I, LEANDER P. BONNELL, a citizen of the United States, residing at North East, in the county of Erie and State of Pennsylvania, have invented certain new and useful Improvements in Devices for Preventing the Creeping of Rails; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to improvements in devices for preventing the creeping of rail-road rails, and has for its object the construction of an anti-creeping device which can be clamped to the base of a rail-road rail so as to be secured against longitudinal slipping thereon, and which device can also be securely spiked to the rail-road cross-tie on each side of the rail. These and other features of my invention are hereinafter set forth and explained, and are illustrated in the accompanying drawings, in which:

Figure 1 is a plan view of my improved anti-creeping device for rail-road rails in place upon a section of said rail. Fig. 2 is a sectional view thereof on the line $x-x$ looking in the direction of the arrow y , in Fig. 1. Fig. 3 is a horizontal section of a portion of my device on the line $z-z$ in Fig. 2.

In these drawings A indicates an ordinary cross-tie, and B an ordinary rail-road rail commonly used in the construction of rail-roads, which rail B is secured to the cross-tie A by means of spikes C in the ordinary manner.

For the purpose of preventing the creeping of the rail in the direction of the arrow w (see Fig. 1) which is usually down grade and in the direction of the traverse of the rail-road trains on double-track roads, I provide a bar D, which is adapted to pass underneath the rail B, and on one end d thereof I construct a box-like inclosure or mortise d (see Fig. 3) which is open on the edge next to the rail and also on the edge next to the cross-tie, in which mortise I secure the end of a bar E by means of a rivet e . The upper wall d^2 of the mortise d preferably overlaps the edge b of the rail B to prevent the end d of the bar D from dropping below the edge b of the rail. This bar E may however, if de-

sired, be an integral part of the bar D, that is, the two bars D and E may be formed as an L-shaped structure. The bar E is also provided with spike holes e' through which spikes may be driven into the tie A.

The bar E is preferably constructed with a shoulder E' thereon, and in the space E between the shoulder E' and the side B of the box-like mortise d I place a hardened steel block F' which is provided with sharp teeth f , adapted, under sufficient pressure, to cut into the edge b of the base of the rail B. Upon the opposite end d' of the bar D I pivot a bar G by means of a rivet g , which bar G is provided with a cam G' having a groove g' (see Fig. 2) adapted to embrace the edge b' of the base of the rail B, in order to prevent the cam G' from dropping below the edge b of the base of the rail B.

In operation the lever G is thrown backward until it is substantially in line with the bar D. The toothed block F' is placed in the space or pocket E with the teeth f thereof on toward the rail, and the bar D is passed under the rail B, and the end d of the upper wall d^2 of the mortise d hooked over the edge b of the rail B with the bar E upon the cross-tie A beside the rail B. The lever G is then forced around to the position shown in Fig. 1, where it is secured by the spike g' driven through a hole therein (not shown) and into the cross-tie A. The forcing around of the lever G as above described acts to draw the teeth f of the block F' into the edge b of the rail B, and thereby secure the device against longitudinal movement on the base of the rail B. The bar E is then secured to the cross-tie A by means of spikes driven through holes e' therethrough and into the cross-tie A.

It will thus be seen that in the structure hereinbefore described I have an anti-creep device for rail-road rails that is not only capable of being secured upon the rail against longitudinal movement thereon, but one which also is capable of being secured to the cross-tie upon each side of the rail B, thus insuring a straight-away endwise pull upon all parts thereof.

Having thus described my invention so as to enable others to construct and operate the same what I claim as new and desire to secure by Letters-Patent is:

1. In an anti-creep device for rail-road rails a bar adapted to pass transversely underneath the rail adjacent to a cross-tie, means to connect each end of said bar to said

cross-tie, a toothed jaw on one end of said bar at one side of a rail-road rail, and means on the other end of said bar at the opposite side of said rail adapted to cause the toothed jaw to bite into the base of said rail, substantially as set forth.

5. The combination in an anti-creep device for rail-road rails, of a bar adapted to pass transversely underneath the rail having 10 a box-like mortise on one end thereof, a toothed block in said mortise adapted to bite into the edge of the base of a rail-road rail, a bar secured to said transverse bar adjacent to said toothed block and to the cross-tie, 15 and a cam-lever on the opposite end of said transverse bar adapted to clamp the rail between said toothed block and said cam; the free end of said lever being adapted to be secured to said cross-tie, substantially as and 20 for the purpose set forth.

3. In an anti-creep device for rail-road rails the combination of a bar adapted to be inserted transversely under a rail-road rail adjacent to a cross-tie, means adapted to 25 maintain a fixed distance between said cross-tie and said bar, a toothed block, means to secure the same upon one end of said transverse bar, clamping means on the opposite end of said transverse bar adapted to clamp 30 a rail against said toothed block and means adapted to retain said clamp in a closed position, substantially as set forth.

4. In an anti-creep device the combination with the cross-tie and rail, of a bar spiked to 35 said tie, another bar secured to the free end of said first mentioned bar and passing transversely underneath said rail, a toothed jaw secured to said transverse bar on one side of said rail, a clamp cam pivoted to the other 40 end of said transverse bar at the opposite side of said rail, and a lever to operate said cam

adapted to be spiked to said cross-tie, substantially as set forth.

5. In an anti-creep device for rail-road rails the combination with a cross-tie and rail, of a bar adapted to be secured to said tie with the free end thereof projecting over the side of the cross-tie, a transverse bar secured to the free end of said first mentioned bar, a toothed jaw on the end of said transverse bar at one side of said rail, means to prevent said toothed jaw from falling below the edge of the base of said rail, a clamp-cam pivoted on the other end of said transverse bar at the opposite side of said rail, means to prevent said cam from falling below the edge of the base of said rail, and a lever to operate said cam and adapted to be secured to said cross-tie when the clamp-cam is closed against the edge of the base of the rail, substantially as set forth.

6. In an anti-creep device for rail-road rails, a transverse bar having a lip at one end thereof adapted to overlap the edge of the base of the rail, and a mortise-like pocket between said lip and the body of said bar, a toothed block adapted to be placed within said pocket, a cam pivoted on the opposite end of said transverse bar having a lip overhanging the bearing face thereof adapted to overlap the edge of the base of the rail, and means adapted to rigidly secure each end of the transverse bar at the desired distance from a cross-tie, substantially as and for the purpose set forth.

In testimony whereof I affix my signature, in presence of two witnesses.

LEANDER P. BONNELL.
